UNITED STATES PATENT OFFICE.

PIERRE ALEXANDRE DARRACQ, OF LE PRÉ ST. GERVAIS, FRANCE.

SEWING-MACHINE.

SPECIFICATION forming part of Letters Patent No. 425,539, dated April 15, 1890.

Application filed January 24, 1889. Serial No. 297,404. (No model.) Patented in France October 8, 1888, No. 193,383; in England November 3, 1888, No. 15,905, and in Switzerland March 2, 1889, No. 529.

To all whom it may concern:

Be it known that I, PIERRE ALEXANDRE DARRACQ, mechanical engineer, a citizen of the Republic of France, residing at Le Pré St. Gervais, in France, have invented an Improved Sewing-Machine for Corsets, (for which I have applied for Letters Patent in Switzerland, March 2, 1889, No. 529; in England, No. 15,905, dated November 3, 1888, and in France, No. 193,383, dated October 8, 1888,) of which the following is a specification.

The object of the present invention is to provide a machine for producing the fan-like arrangement of stitches which occurs in the manufacture of corsets, the object of which is to secure the ends of the whalebone or "stays;" and the invention consists, essentially, in an arrangement of mechanism for displacing the head of the machine for producing the longitudinal stitches and the corset in a transverse direction either to the right or to the left in such a manner that the needle descends at suitable places to produce the peculiar fan-like arrangement of stitches instead of displacing the corset only in both directions.

In the accompanying drawings, Figure 1 represents the fan-like arrangement of the stitches produced from the left to right; and Fig. 1bis is a similar view, the stitches being produced from the right to the left. Figs. 2 and 2bis, joined at the lines Y⁶ Y⁶, represent a side elevation of the machine partly in section. Fig. 3 is a plan of the head of the machine and the presser-feet, all other parts being removed. Figs. 4 and 4bis, joined together at the lines Y⁷ Y⁷, represent a plan of the under side of the machine, part of the head being removed. Figs. 5 and 5bis, joined together at the lines Y⁸ Y⁸, represent a projection or developed view of the driving cam-wheel. Fig. 6 is a vertical section of the machine on lines X⁵ X⁵ and X⁶ X⁶ of Figs. 2 and 2bis, looking toward the front of the machine. Fig. 7 is a front elevation of the machine. Fig. 8 represents a special arrangement for starting the machine. Fig. 9 is a side elevation of the mechanism for changing the direction of rotation of the feed-wheels. Fig. 10 is a perspective view of the sector, eccentric, and a portion of the disk.

In Figs. 1 and 1bis, a represents the end of

the whalebone or stay confined by the fan-like stitches from left to right in Fig. 1 and from right to left in Fig. 1bis. The corset is placed in position on the machine, and when the machine is started the needle will make two stitches 0.00 in the same place, so as to lock each other and thus form a strong beginning. The corset is then displaced transversely to make stitch 1 of the fan. After this the head of the machine is displaced without moving the corset for making stitch No. 2. The corset is then displaced laterally a distance equal to the thickness of the thread and the sewing mechanism correspondingly in the longitudinal sense for making stitch 3. The head of the machine is then displaced again for making stitch 4, and so on until the fan is finished, when the corset is once more displaced laterally to make a double interlocking stitch 25 26, the same as was made at the beginning. The machinery that I have constructed has therefore to displace the corset in one direction and the sewing parts of the machine in another direction. Moreover, the longitudinal displacement must vary constantly in length to a considerable extent, the greatest displacement being between the first two stitches of the fan and the smallest between the last two stitches. Moreover, the stitches which are parallel to the edge of the whalebone or stay have to be in a straight line, while those confining the end of the whalebone or stay have to be arranged in the arc of a circle or in a form corresponding with said end. Lastly, the machine is to stop automatically as soon as the fan is completed.

The machine comprises, essentially, all parts of an ordinary sewing-machine, and in addition special mechanical arrangements for the automatic displacement of the corset and the sewing parts of the machine and for the stopping of the machine when the fan is completed.

The horizontal displacement of the head A of the machine is effected by means of a cam-wheel S, which also regulates the amplitude of the stitches. To this end the head A of the machine oscillates horizontally between the centers a' a' of a vertical stirrup-piece B, fixed to the frame C, between the vertical

sides of which are mounted all the various parts of the mechanism.

The shaft D, which operates the sewing parts of the machine, is, by means of a link 5 and two knuckle-joints M M or the equivalents thereof, attached to the shaft L, from which it receives its movement, thus permitting the shaft D to follow the horizontal displacement of the head of the machine. On 10 the shaft L is mounted a pitch-wheel N, receiving its motion from a pitch-chain. This wheel N is mounted loosely, but can be engaged with and transmit motion to the shaft L by means of the clutch-coupling O, which is capable of being moved longitudinally on the shaft L, but always turns with it. A spiral spring P, interposed between the clutch-coupling and a collar Q on the shaft L, tends to hold the coupling O in engagement with the 15 clutch-face of the wheel N. The shaft L is mounted in the journals R R', forming part of the frame C of the machine.

The horizontal displacement of the head of the machine is produced by means of the cam-wheel S, the cam-groove of which is represented in projection or developed view in Figs. 5 and 5bis. The horizontal shaft U of the said cam-wheel is supported in a downwardly-projecting arm V of the frame of the 20 machine. The cam-wheel S carries on its face a bevel-wheel V', gearing with the bevel-pinion V'', to which motion is transmitted from the shaft L by means of the miter-wheel X, fixed on the shaft L and gearing with the 25 miter-wheel X', mounted on the shaft L', the bevel-wheel X'', mounted on the same shaft and gearing with a bevel-wheel X''', mounted on the shaft L''', which carries at its lower end the pinion V'', as shown in Fig. 4bis. A 30 roller 1, mounted on the end of a lever 2, the pivot 3 of which is adjustable, is guided in the cam-groove 4 of the cam-wheel S, the sinuosities of which cam-groove correspond with the desired displacements of the head of the 35 machine. The pivot 3 of the lever 2 can be placed in either of the two holes 3', formed in the base of the stirrup-piece B, the end of the lever 2 opposite to that carrying the roller 1 being attached to the bottom part 5 of the 40 head of the machine. Thus the horizontal movements of the roller 1, following the sinuosities of the cam-groove 4, are transmitted to the head of the machine. Thus it will be seen that the so-called "longitudinal stitches" 45 are regulated by the revolution of the cam-wheel S without the corset itself being moved in any way.

To produce the so-called "transverse stitches" of the fan, the corset itself is 50 displaced in a transverse sense under the influence of carriers or feed-wheels arranged underneath the presser-feet. Two arms or standards 6 6' of about the same contour as the head of the machine are fixed one to each of the tops of 55 the stirrup-piece B, and between these arms the head of the machine reciprocates horizontally. Each of the arms or standards 6 6'

is provided with a presser-foot bar and presser-foot 7 7', Fig. 7, arranged to work in the usual manner. Underneath each of these 70 presser-feet 7 7' is a circular serrated carrier or feed-wheel 8 8', mounted, respectively, on the shafts 9 9', which transmit their movement to the wheels 8 8' for the displacement of the corset in a direction transverse to the 75 fan to be formed. To this end the gear-wheels 10 10' are secured on the shafts 9 9', and receive their movement from the corresponding 80 gear-wheels 11 11', fixed on the shaft 12, journaled in the supports 13 13', mounted on the shafts 9 9'. On each side of the gear-wheel 11 one of the supports 14 14' is mounted on the shaft 12. These supports carry at their lower 85 ends a shaft 15, on which is mounted loosely a gear-wheel 16 in the same vertical plane as the 90 wheels 10 and 11. The shaft 15 is attached to a lever 17, pivoted at 18, and adapted to be 95 adjusted to two different positions by means of the spring-button 19, which it carries at its end, and which may be engaged with either of the openings 20 or 21, formed in the indicator 22. Movement is transmitted to the wheels 10 11 16 by means of a pinion 23, mounted on a shaft 24, Figs. 4 and 9, journaled in one side of the frame, and a support 25, attached to the 100 said frame.

As represented in Fig. 2, the pinion 23 operates the wheel 10 through the wheel 11, which is always in gear with the wheel 16, which in this case turns loosely on its shaft. 105 It follows, therefore, that when the pinion 23 turns in the direction of the arrow 26, the wheel 11 turns in the direction of the arrow 26' and the wheel 10 in that of the arrow 26''—that is, toward the left. The lever 17 is in this Fig. 2 represented as having its 110 spring-button 19 in the opening 20 of the indicator 22. If the lever 17 be turned on its pivot 18, so that the spring-button 19 would engage with the opening 21 of the indicator 22, it would follow by the arrangement of the 115 supports and lever 13 14 17 that the angle formed by the supports 13 14 would become more acute, while that formed by the support 14 and lever 17 would become more obtuse, 120 and consequently the wheel 11, although always gearing with the wheels 10 and 16, would be thrown out of gear with the pinion 23, while the wheel 16 would be thrown into gear therewith and thus would transmit motion to the wheel 10 by means of the wheel 11. The 125 wheel 10 would therefore turn in the opposite direction, because, the rotation of the pinion 23 being always in the direction of the arrow 26, the wheel 16 will turn in the direction of the arrow 27, the wheel 11 in that of the arrow 27', and 10 in that of 27''. The two wheels 11 11' being both secured on the same shaft 12, their movement will be transmitted to the 130 wheels 10 10', and through these to the feed wheels or carriers 8 8'.

From the preceding explanation it will be understood that the feed-wheels 8 8' can be made to revolve to the right or the left, ac-

cording to the desired displacement of the corset to the right or the left, by the adjustment of the pivoted lever 17.

The pinion 23 receives its motion in the following manner: On the shaft 24 of this pinion 23 is mounted a disk 28, formed on its face with a recess 29, in the interior of which engages a sector 30, operating by friction on the wall of said recess. This sector is mounted 5 loosely on the eccentric socket 30' of the lever 31, pivoted on the shaft 24. This lever is connected to the lever 32 by means of slots and bolt and nut 36, the lever 32 being pivoted to the side of the frame at 33. The oscillation 10 of the lever 32 is produced by means of a cam-wheel 34, the cam-groove of which operates on a roller 35, carried on the said lever. The point of connection between two levers 31 32 is adjustable by means of the bolt and 15 nut 36. The oscillation of the lever 32, produced by means of the cam 34, is transmitted to the lever 31, which, by means of the eccentric socket 30' and through the medium of the clutch-sector 30, operates the disk 28. 20 The moving of the sector 30 is effected as follows: The lever 31, moving from its lower to its higher position, forces the sector 30, by means of the eccentric socket 31', against the outer wall of the recess 29 of the disk 28, forming a clutch. The upward movement of the lever 31 continuing, the sector 30 will force the disk 28 to turn from right to left, and this 25 rotary movement will continue until the lever 31 has attained its highest point. During the downward movement of the said lever the sector is drawn back or prevented from binding by a suitable spring 29' until the next upward movement of the lever commences. The disk 28 is prevented from following the 30 turn movement of the sector and lever and from moving freely in either direction by means of the friction-brake 28' engaging its periphery, as shown in Fig. 2.

The manner of adjusting the combined 45 length of the levers 31 32 by means of the bolt and nut 36 permits of the amplitude of the oscillation of the lever 31 being regulated, and consequently provides for the necessary 50 regulation of the rotary movement of the disk 28 and that of the feed-wheels 8 8' by means of the above-described intermediate gearing. The cam 34 is mounted on the shaft 36', on which is also mounted a bevel-wheel 37, gearing with a bevel-pinion 38, mounted on an inclined shaft 39, carrying at its other end the bevel-pinion 40, gearing with the bevel-pinion 41, mounted on the shaft L', which receives 55 its rotary motion as before described.

It has herein been previously explained 60 that as soon as the last double stitch 25 26 of the fan has been made the machine stops automatically. This automatic stopping is effected by the following arrangement: The principal cam-wheel S is provided with a 65 spring-button S', to which is fixed a pin S'', which, when the cam-wheel has completed its revolution—i. e., when the fan is finished—

comes in contact with the end of a lever T', pivoted at T'' and extending above this pivot. This upward extension of the lever T' bears 70 against an arm U', mounted on the shaft T'', which carries the uncoupling-fork V''', which, turning with said shaft from right to left, immediately disengages the clutch-sleeve O from the wheel N and instantly stops the machine. 75 To start the machine again it is only necessary to draw forward the pin S'' by the spring-button S', when, the said pin ceasing to bear against the lever T', it (the lever T') will immediately return to its normal position under 80 the influence of the spring P, which also again throws the coupling-sleeve O into engagement with the clutch-face on the wheel N, thus turning the fork V''' with the shaft U'' and the arm U', which latter returns the 85 lever T' to its normal position. This operation of starting the machine, instead of being done by drawing the spring-button S' forward by hand, may be done by a simple movement of the knee, which arrangement is 90 represented in Fig. 8, and has the advantage of leaving the hands entirely free for the maintaining and guiding of the corset on the machine. This arrangement consists of a lever 50, pivoted at about its middle at 51 to a 95 bracket or projection 52 on the frame C of the machine. One end 50' of this lever is bent inward toward the cam-wheel S, the extreme end of it standing exactly opposite the pin S'' when the latter has pressed the lever 100 T' aside and thus stopped the machine. The other end of the lever 50 is pivoted to a bell-crank lever 53 54, pivoted at 55 to a bracket or projection on the frame C of the machine. The arm 54 of the bell-crank extends to the 105 front of the machine, where it is provided with a plate 56, against which the knee of the operator is pressed when it is desired to start the machine. A suitable spring 57 returns the lever 54 to its normal position. 110

It is evident that a pressure on the plate 56 will have the same effect as the drawing forward by hand of the spring-button S', as the end 50' of the lever 50 will push the pin S'' as soon as the lever 54 is pressed aside by 115 the knee of the operator.

The shuttle-carrier E, which acts in combination with the needle K, is operated by the shaft D and receives a differential intermittent movement with reference to the said shaft 120 D. The object of this differential intermittent movement is to seize the needle-thread sharply and to pass it rapidly around the shuttle and then to give time to the needle and to the tension device to draw the thread 125 and to displace themselves in the longitudinal sense for the next longitudinal stitch. To this end the shuttle-carrier E is mounted on a small spindle E', journaled in the support E''. The said spindle E' extends beyond the 130 support E'' and carries on its extreme end a pinion F'. On the forward end of the shaft D is mounted a disk F'', formed with a recess in its face, part of the wall G' of which recess

is provided with teeth G'' , which, gearing with the pinion F' , extending into the recess, turns this pinion, and with it the shuttle-carrier E . The rotary movement of the pinion F' of course ceases as soon as the last tooth of the sector G'' has passed it, and the said pinion remains stationary until the teeth engage again with it during the next revolution of the disk F'' .

10. The feeding of the thread, as in the ordinary machines, is effected by means of the tension and take-up devices $H' H''$, the latter being operated by the cam-wheel H''' , mounted on the shaft D .

15. I claim—

1. In a sewing-machine for corsets, the combination, with head A , of a cam-wheel S , having a cam-groove 4, a horizontal lever 2, working on an adjustable pivot 3 and connected 20 to the head A so as to impart to it oscillating motion, a stirrup-piece, such as B , and a pinion V'' , gearing with a bevel-wheel V' , the said pinion V'' receiving motion from the driving-wheel N by means of the intermediate gearing X''', X'', X' , and X , substantially as and 25 operating in the manner and for the purpose herein described, and illustrated in the accompanying drawings.

2. In a sewing-machine for corsets, the combination, with the feed-wheels 8 8', mounted on the spindles 9 9', of gearing for operating them, consisting of the wheels 10 10' 11 11', to which movement is imparted by a small pinion 23, mounted on the shaft 24, on which is also 35 mounted the recessed disk 28, in the recess of which engages the eccentric sector 30, which rotates the said disk, the sector being operated by the jointed lever 31 32, the combined length of which is adjustable, and 40 which receives its motion from the wheels and pinions 37, 38, 40, 41, X , and X' , substantially as and operating in the manner herein described, and illustrated in the accompanying drawings.

45. 3. In a sewing-machine for corsets, the combination, with the feed-wheels 8 8', of a pinion 23, operated by a disk, wheels 10, 10', 11, and 16, shaft 15, supports 13, 14, and 14', lever 17, spring-button 19, and indicator 22, with holes 50 20 or 21, substantially as herein shown and described.

4. In a sewing-machine for corsets, the combination, with a laterally-movable head carrying the needle, thread-hook, and stitch-forming mechanism, of feed-wheels having a variable movement for feeding the corset at right angles to the line of movement of the head, whereby the distance between the stitches formed by said head movement may be increased or diminished, substantially as described.

5. In a sewing-machine for corsets, the combination, with the laterally-movable head, and the needle, thread-hook, and stitch-forming mechanism mounted thereon, and the feeders, of a cam or equivalent device for shifting the head laterally and connections between said

cam and feeders geared to move the feeders between alternate reciprocations of the needle, whereby the long or alternate stitches 70 may be formed parallel, substantially as described.

6. In a sewing-machine for corsets, the combination, with the laterally-movable head, the needle, thread-hook, and stitch-forming mechanism mounted thereon, and the feed-wheels, of a cam for shifting the head laterally, connections between said cam and feed-wheels, and a cam interposed in said connections for moving the feed-wheels between alternate reciprocations of the needle, substantially as described.

7. In a sewing-machine for corsets, the combination, with the laterally-movable head carrying the needle and complemental stitch-forming mechanism, of the reversible feeders for feeding the material in either direction at right angles to the line of movement of the head, substantially as described.

8. In a sewing-machine for corsets, the combination, with the laterally-movable head carrying the needle and complemental stitch-forming mechanism, of the feed-wheels, a driving mechanism therefor, and a reversing-gear interposed between the driving mechanism and feed-wheels, whereby the direction of feed may be reversed, substantially as described.

9. In a sewing-machine for corsets, the combination, with the laterally-movable head carrying the needle and complemental stitch-forming mechanism, of the feed-wheels, a pinion moved by the driving mechanism, a gear-wheel connected to the feed-wheels, and two movable gears meshing with said wheel and 105 with each other, and a lever for moving either of said gears into mesh with the pinion, whereby the direction of rotation of the feed-wheels may be reversed, substantially as described.

10. In a sewing-machine for corsets, the combination, with the laterally-movable head pivoted on a fixed center and the feeding mechanism, of a rotary cam-wheel for moving said head, having a sinuous groove conforming 115 to the desired lateral displacement of the head, whereby stitches of varying design may be formed, and an arm connected to the head and guided in said groove, substantially as described.

11. In a sewing-machine for corsets, the combination, with the laterally-movable head pivoted on a fixed center and carrying the needle-bobbins and thread-hook, a rotary cam having a sinuous surface, and an arm connected to 125 the head and guided by said cam, of a shaft for driving the needle and hook, having a universal coupling therein, whereby the lateral movement of the head is permitted, substantially as described.

12. In a sewing-machine for corsets, the combination, with the laterally-movable head carrying the stitch-forming mechanism and a cam for shifting said head, having a sinuous

surface conforming to desired displacement of the head or the figure to be formed, of a driving mechanism, a clutch for throwing the same into engagement, and a stop on the cam 5 for throwing the clutch out of gear upon the completion of a figure, substantially as described.

13. In a sewing-machine for corsets, the combination, with the laterally-movable head pivoted in vertical bearings to swing horizontally and carrying the stitch-forming mechanism, the feeders, and a cam for shifting the head laterally, of an arm connected to the head, pivoted on an adjustable center, and engaging the cam, substantially as described.

14. In a sewing-machine, the combination, with the feed-wheels, of a disk or equivalent connected thereto, a clutch engaging said disk, a lever connected to said clutch, a pivoted 20 lever operated by the drive mechanism, and an adjustable connection between said levers whereby the rate of feed may be varied, substantially as described.

15. In a sewing-machine, the combination, 25 with the feed-wheels, of a disk or equivalent connected thereto, a lever connected to said clutch, a lever pivoted on a fixed center and connected to the first lever by an adjustable connection, and a cam for moving said levers, substantially as described.

16. In a sewing-machine, the combination, with the laterally-movable head pivoted on a

fixed center and carrying the needle, thread-hook, and stitch-forming mechanism, of the feed-wheels, and a rotary cam for shifting 35 said head laterally, having its cam-surface conforming to the desired displacement or figure to be formed, and having a straight portion at the beginning and end, whereby more than one stitch is formed at said points 40 to lock the same, substantially as described.

17. In a sewing-machine, the combination, with the laterally-movable head carrying the needle, thread-hook, and stitch-forming mechanism, of a cam for shifting said head laterally, having its cam-surface conforming to the desired displacement or figure to be formed, and having a straight portion at the beginning and end of its cam-surface, whereby the head remains stationary during two 45 strokes of the needle, and feeders connected to said cam and geared to feed only between alternate strokes of the needle, whereby the stitch may be locked by two strokes of the needle in the same place, substantially as described.

In testimony whereof I have hereunto subscribed my hand in the presence of the two subscribing witnesses.

PIERRE ALEXANDRE DARRACQ.
